CLOCK

Jerry Cumbus, Sausalito, Calif., assignor of one-half to Irene O. Kursh, Palo Alto, Calif.

Filed Aug. 8, 1960, Ser. No. 61,658

Term of patent 7 years

(Cl. D42—7)

FIG. 1

FIG. 1 is a front elevation of a clock embodying my new design.

FIG. 2 is a top plan view of the clock shown in FIG. 1.

FIG. 3 is a bottom plan view of the clock shown in FIGS. 1 and 2.

FIG. 4 is a fragmentary cross-sectional view thereof, taken on line 4—4 of FIG. 2.

I claim:

The ornamental design for a clock, substantially as shown.
